UNITED STATES PATENT OFFICE.

JOHN TALIAFERRO THOMPSON, OF NEWPORT, KENTUCKY, ASSIGNOR, BY DIRECT AND MESNE ASSIGNMENTS, TO AUTO-ORDNANCE CORPORATION, OF NEW YORK, N. Y., A CORPORATION OF NEW YORK.

AMMUNITION LUBRICATION.

1,370,617.

Specification of Letters Patent.

Patented Mar. 8, 1921.

Application filed May 10, 1920. Serial No. 380,050.

To all whom it may concern:

Be it known that I, JOHN TALIAFERRO THOMPSON, citizen of the United States of America, and resident of Newport, in the county of Campbell and State of Kentucky, have invented new and useful Improvements in Ammunition Lubrication, of which the following is a specification.

This invention relates to a new and improved method and means adapted for use in lubricating ammunitions in connection with guns.

In the use of high powered arms with the types of fixed ammunition now in general use very high powder pressures are developed. The metallic cartridge case is thus very suddenly and powerfully pressed into contact with the walls of the powder chamber. The cartridge cases are formed of relatively soft metal such as copper alloys and are deformed by this pressure and caused to conform to the contour of the powder chamber. Theoretically the cartridge exactly fits the chamber but actually it does not do so owing to the necessary tolerances of manufacture and to the variation in the chamber dimensions due to wear or erosion. These latter factors are fruitful sources of minute irregularities in the chamber surface.

Due to these several causes the extraction of the cartridge casing after firing the charge is rendered difficult. This is particularly true in types of automatic or semi-automatic arms where the casing is extracted or started on its rearward movement before the pressure of the discharge is entirely relieved. In this case the pressure tends during the movement to hold the cartridge walls intimately engaged with the chamber walls.

This tendency of the cartridge shell to stick in the chamber, if it has no other ill effects, serves to render more difficult the operation of manually operated arms and in the case of automatic or semi-automatic arms, it slows up the motion and puts an excessive strain on the parts co-operating to extract the cartridge.

In more extreme cases, however, either where the chamber is badly eroded or worn

or where the cartridge is badly out of normal contour or is weakened at some points, this sticking causes the extractor to rupture the cartridge shell and only extracts the base portion. When the engagement of the shell is sufficiently firm to cause this result, the extraction of the shell fragment remaining in the chamber is quite difficult and the piece is out of action for a time. In hand operated arms the user may not notice that the shell was ruptured and may attempt to force in a new cartridge for the next shot, which will further complicate matters, and there will also be the possibility of a dangerous discharge of the second cartridge while not fully seated in the chamber. In the automatic or semiautomatic guns these results also follow, causing a jam difficult to remove and injurious to the piece.

Further in the use of arms having a rotating breech closure there is a tendency for the closure in rotating, to turn with it the cartridge against whose base it is pressed and thus to screw the cartridge shell into any irregularities existing in the chamber or on the breech closure face.

I have determined that these several difficulties may be substantially eliminated by the proper lubrication of the cartridge before its entry into the chamber. Certain means and methods for accomplishing this result have been disclosed in my Patent No. 1,307,066 dated June 17, 1919.

In the present application I have disclosed an improved plate oil pad for lubricating ammunition, the means comprising a separate removable element which may be readily used in connection with existing guns and magazines.

It is an object of my invention to provide new and improved means adapted to be fitted into a gun or magazine and to lubricate the ammunition as it is fed from the magazine to the chamber of the piece. It is an object to provide such means so constructed that it may be readily inserted and removed from guns and magazines of existing types. It is also an object to provide a lubricating element adapted to lubricate all necessary surfaces of the cartridge. It is a further ob-

ject to provide a lubricating device which is simple in construction, positive in its action and relatively inexpensive to manufacture. Other and further objects will appear as the 5 description proceeds.

I have illustrated certain preferred embodiments of my invention in the accompanying drawings in which,—

Figure 1 is a longitudinal section of the 10 breech portion of a gun showing my invention in place;

Fig. 2 is a cross section on line 2—2 of Fig. 1;

Fig. 3 is a horizontal section through my 15 device with cartridges shown therein;

Fig. 4 is a longitudinal section showing my invention in position in a detachable box magazine;

Fig. 5 is a cross section on line 5—5 of the 20 device shown in Fig. 4; and

Fig. 6 is a horizontal section of Fig. 4.

In Fig. 1 I have shown my improved removable plate oil pad in position in the magazine of the Springfield rifle of the style 25 now in use by the army and officially known as United States rifle, caliber 30, model of 1903. The rifle itself forms no part of the present invention and comprises the barrel 7, receiver 8, bolt 9, guard 10, floor plate 11, 30 magazine spring 12 and follower 13.

My improved lubricating device comprises the metal or other base plate 14 which is shaped to conform to the interior contour of the magazine and the lubricating pad 15 35 which, as shown in Figs. 1 to 3, is attached to the face of the plate 14 by the rivets 16. This pad closely engages the cartridges in the magazine as is shown in Figs. 2 and 3 and contacts with each cartridge.

40 In Figs. 4, 5 and 6, I have shown my invention applied to a box magazine of the type comprising the body member 17, the rear attachment member 18, the follower 19, the follower spring 20, and bottom closure 45 21. The magazine is shown containing the cartridges 22. The lubricating plate device is fitted just inside the body of the magazine and comprises the plate 23 and the lubricating member 24 attached to the plate by the 50 stitching 25 which passes through suitable holes in the plate.

In both forms of my device the plate may be formed of metal, indurated fiber or any suitable material which possesses sufficient 55 strength and stiffness. The lubricating pad proper may be formed of any absorbent material such as felt or flannel or may be formed of an absorbent mass covered by fabric through which the lubricant passes.

60 My lubricating device may be applied to existing magazines of any type, two such applications having been illustrated by way of example. No modification of existing structure is required except that if the following fits the magazine too closely to permit

the lubricating plate to pass between the magazine walls and the follower, the latter may be reduced in size or a smaller follower substituted. The usual magazine is made of a size to permit sufficient play of the cartridges so that the lubricating device, which is relatively thin, may be inserted without so reducing the interior space as to preclude the admission of the usual number of cartridges.

70 The lubricating device is inserted in fixed magazines of the type shown in Fig. 1 by removing the floor plate 11 and inserting the lubricator upwardly. The device is similarly inserted in magazines of the type 75 shown in Figs. 4 to 6 by removing the bottom closure 21.

When the device becomes worn it may readily be removed in this manner and a new one substituted. If the lubricant becomes exhausted before the pad is worn, the device may be removed and again treated with the lubricating material and replaced in the magazine.

80 It will be noted that my lubricator in the form shown in Figs. 1 to 3 acts to lubricate the bases of the cartridges. This is essential in firearms such as the Springfield where the bolt is locked by a rotary motion while thrusting against the cartridge. In the form 85 shown in Figs. 4 to 6 the base of the cartridges are not lubricated. These cartridges and magazines as usually used in guns having inertia breech closures or closures of the "Blish angle" type which do not rotate and 90 hence base lubrication is not essential.

In both forms shown the sides of the bullet as well as the cartridge case are lubricated and in the form of Figs. 4 to 6, as 95 shown in Fig. 6, the forward portion of the lubricating pad is curved inward to contact with all portions of the bullets.

100 My improved plate lubricating pads may obviously be formed in any desired or necessary shape to lubricate particular types of 110 ammunition or to fit magazines of varying contours and capacities.

I claim:—

1. A device for lubricating cartridges in gun magazines comprising a cartridge lubricator adapted to be detachably fitted into a magazine with portions extending along opposite sides of the cartridge space in position to contact with the cartridges therein.

115 2. A device for lubricating cartridges in gun magazines having a lubricating element adapted to contact with the bases of cartridges placed in the magazine.

120 3. A removable device for lubricating cartridges in gun magazines having a lubricating element adapted to contact with the sides and bases of cartridges placed in the magazine.

125 4. A removable device for lubricating cartridges in gun magazines comprising a

base plate and a lubricating pad secured thereto, the device being adapted to be detachably fitted in the magazine of a gun.

5. A removable device for lubricating cartridges in gun magazines adapted to be fitted about the sides and at least one end of the magazine.

6. A removable device for lubricating cartridges in gun magazines comprising a base plate and a lubricating pad attached thereto, the device being adapted to be fitted in the magazine of a gun and fitting about the sides and at least one end of the magazine.

10 7. A removable device for lubricating cartridges in gun magazines, U-shaped in

form and adapted to be fitted in a magazine along opposite sides thereof.

8. A removable device for lubricating cartridges adapted to be fitted in a gun 20 magazine, the device comprising a base plate and a lubricating element substantially coextensive therewith.

9. In combination with a cartridge magazine having a cartridge passageway therein, 25 a hollow cartridge lubricator adapted to telescope into said passageway from one end thereof with portions lying along opposite sides of the passageway.

Signed by me at Boston, Massachusetts, 30 this twenty-ninth day of April, 1920.

JOHN TALIAFERRO THOMPSON.
